UNITED STATES PATENT OFFICE.

WILLIAM S. GRAFTON, OF WHEELING, WEST VIRGINIA, ASSIGNOR TO THE WHEELING CORRUGATING COMPANY, OF SAME PLACE.

DESIGN FOR A CROSS-PIECE FOR METALLIC MOLDING.

SPECIFICATION forming part of Design No. 23,049, dated February 6, 1894.

Application filed January 8, 1894. Serial No. 496,195. Term of patent 7 years.

To all whom it may concern:

Be it known that I, WILLIAM S. GRAFTON, a citizen of the United States, residing at Wheeling, in the county of Ohio and State of West Virginia, have invented and produced a new and original Design for a Cross-Piece for Metallic Molding, of which the following is a specification, reference being had to the accompanying drawing, forming part hereof, which shows a cross-piece for metallic molding designed according to my invention.

My design consists of a cross piece for metallic molding ornamented as follows.

In general outline the cross-piece is square, and at its four corners there is a concaved, circular projection a , joined together by four ribs or ridges a' . Midway between the corners, the ribs or ridges join concaved, circular projections a^2 . In the center of the square there is a concaved, circular projection B , from which radiates a series of pear-shaped projections b , between which is radially arranged a series of bars b' , having knobs b^2 on their outer ends. Around this central figure is arranged a rectangular series of pyramidal projections C , and from each side of the figure formed by the pyramidal projections radiates a series of curved ribs D , extending to the corresponding rib a' , at the edge of the plate. Within the ribs D , there is a curved rib d , from which radiates a series of depressions d' . In each corner of the square bounded

by the ribs a' , there is a curved projection E , which connects with a downwardly sloping portion E' , which extends to the outer corner 35 of the plate. Each of these corner portions is ornamented with a triangular projection c , around which is arranged a series of curved ribs or projections e' , which join each other at their outer ends. 40

Between the corner portion of the plate and the ribs D , are arranged two triangular projections F , and a central bird-shaped projection G . The four edges of the plate extend for a short distance beyond the four ribs a' . 45

The essential feature of my design is a cross-piece for metallic molding having a central figure formed by a concaved circular projection from which radiates a series of pear-shaped projections, with ribs or bars between 50 them, and surrounded by a series of pyramidal projections from which radiate curved ribs or projections, the four corners of the cross-piece having curved ribs or projections and concaved portions ornamented by curved ribs. 55

I claim—

The design for a cross-piece for metallic molding herein shown and described.

In testimony whereof I have hereunto subscribed my name.

WILLIAM S. GRAFTON.
